(57) **CLAIM**

The ornamental design for a robotic upper body, substantially as shown and described.

DESCRIPTION

FIG. 1 is a front perspective view of one embodiment of a robotic upper body.

FIG. 2 is a front elevation view of the robotic upper body of FIG. 1.

FIG. 3 is a front elevation view of the robotic upper body of FIG. 1.

FIG. 4 is a right-side view of the robotic upper body of FIG. 1.

FIG. 5 is a left-side view of the robotic upper body of FIG. 1.

FIG. 6 is a top view of the robotic upper body of FIG. 1.

FIG. 7 is a bottom view of the robotic upper body of FIG. 1; and,

FIG. 8 is a rear perspective view of the robotic upper body of FIG. 1.

The broken lines in the drawings depict portions of the robotic upper body which form no part of the claimed design.

1 Claim, 7 Drawing Sheets
